BATTERY LIGHT

Harry T. Kingsbury, Keene, N. H., assignor to
 Kingsbury Mfg. Company, Keene, N. H., a corporation of New Hampshire

Application April 29, 1933, Serial No. 668,646

11 Claims. (Cl. 240—10.61)

The present invention relates to improvements in electric battery lamps, and more particularly to improvements in portable electric battery lamps of the flashlight type.

5 An object of the present invention is to provide an improved portable electric lamp, of the type referred to, wherein a cap member, which is adapted to aid in supporting a light bulb and switch mechanism, is adapted to be fitted directly over the terminal end of an electric battery and to be frictionally held thereon.

10 A further object of the invention is to provide a flashlight, of the type referred to, wherein the light support fits within an opening in the cap member and is adapted to telescope therein and wherein resilient means are adapted to act upon the light support to normally hold the light bulb terminal out of contact with the battery terminal.

15 A further object of the present invention is to provide an improved light support and switch unit which may be directly applied to and held by friction on the terminal end of the battery.

20 A still further object of the invention is to provide an improved unit, of the type referred to, which may be applied to the terminal end of an electric battery and which is adapted to effect an intermittent or continuous lighting circuit.

25 A still further object of the invention is to provide, in a device of the character referred to, an improved light support and friction ring in interfitting relationship and normally held apart by a spring member and a cap member which is adapted to aid in holding the component parts together and which is provided with means for effecting a continuous lighting circuit when the light support is slightly turned.

30 The invention still further aims to provide an improved cap assembly, of the type referred to, which may be applied directly to a battery whereby to provide an inexpensive flashlight which is readily assembled and which is efficient in operation to afford either continuous or intermittent illumination.

35 These and other objects of the invention will appear obvious and will be hereinafter more fully described.

In the drawing:

40 Figure 1 is a perspective view showing the completely assembled flashlight unit.

45 Fig. 2 is a side elevation, partly in section, showing the cap assembly with the circuit open.

50 Fig. 3 is a similar view showing the relative position of the parts when the circuit is closed.

Fig. 4 is a bottom plan view of the cap assembly.

Fig. 5 is a fragmentary view of the cap member when used with another form of battery.

5 In general, the present invention aims to provide a novel light support and switch assembly which may be directly applied to and frictionally held on the terminal end of the usual dry cell battery whereby to provide an inexpensive flashlight. A cap member is adapted to frictionally engage the side of the battery and is provided with a central opening above the battery top. A light supporting member and a friction ring are loosely connected to prevent disengagement from the action of an enclosed coil spring which normally holds the same apart, but the connection is such that the light support may be moved toward the battery top when pressure is applied. The friction ring rests upon the top of the battery and encircles the battery terminal. The depending edge of the opening in the cap member is provided with cam surfaces which are engaged by lugs on the light support to prevent disengagement thereof but to permit a telescoping movement of the light support within the opening in the cap member so that the light terminal may contact with the battery terminal when the light support is depressed toward the battery. When the light support is turned in a clockwise direction, the lugs thereon will pass over the cam surfaces and so cause the light support to descend within the opening in the cap member whereby the light terminal may be held in contact with the battery terminal in order to provide a continuous lighting effect.

35 Referring more in detail to Figures 1—4 of the accompanying drawing, one form of dry cell battery 10 is shown with the usual fibrous covering 11 and metal jacket 12 which is provided with a metal top closure 13 through which extends the battery terminal 14. Suitable insulating composition 15 prevents contact between the metal top and the battery terminal. A bottom closing member 16 may be fitted over one end of the battery and frictionally held thereon to prevent extraneous matter from contacting therewith. A cap member 17 is provided with an offset depending skirt 18 which may be slipped on the terminal end of the battery and frictionally held thereon. The offset portion 19 of the cap member 17 is 50 adapted to rest upon the top of the battery in order to insure the proper assembly of the various parts to be hereinafter described. There extends upwardly from the offset portion 19 of the cap member 17 a vertical wall 20 which is inward- 55

ly bent to provide a depending skirt portion 21 thus providing a central opening through the top of the cap member. The depending skirt portion 21 is provided with a series of cam or wedge surfaces 22 the function of which will be described hereinafter.

A dome-shaped member 23 is provided with a central opening and an angular projection 24 which permit the threaded end 25 of a light bulb 10 26 to be screwed therein whereby the bulb is supported. The depending edge of the light supporting member 23 is provided with a series of outwardly extending lugs 27 which are adapted to engage the edges of the wedge surfaces 22 of the cap member 17 in order to prevent the light support from becoming disengaged from the cap member. The light supporting member 23 is also provided with a series of alternately spaced inwardly extending lugs 28 which are adapted to engage the bottom face of the horizontal flange 29 of a friction ring 30. The lower edge of the friction ring 30 is bent to provide a channel 31, the bottom of which rests upon the surface of the metal top 13 of the battery 10 and encircles the battery terminal 14. A coil spring 32, having one end seated in the channel portion 31 of the friction ring 30 and the other end thereof pushing against the under surface of the light supporting member 23, is adapted to normally hold the light supporting member in the position shown in Fig. 2 whereby the terminal 33 of the light bulb 26 is out of contact with the battery terminal 14. In this position, the lugs 27 engage the reduced edges of the wedge faces 22 on the cap member 35 and the lugs 28 engage the under face of the flange 29 of the friction ring 30. It is thus apparent that the light supporting member cannot become disengaged and it is also apparent that the electric circuit is open.

40 When it is desired to merely flash the light bulb on, it is simply necessary to press down with a finger upon the light support 23 to overcome the spring action so that the light terminal 33 will contact the battery terminal 14 so that an electric circuit is completed between the battery terminal through the light bulb, light support and friction ring to the metal top 13 of the battery cell. Then, when pressure is released from the light support 23, it will be urged back by the action of the spring 32 to the position shown in Fig. 2. 45 If it is desired to continuously close the electric circuit so that the light bulb will remain illuminated, it is necessary to merely rotate the light support 23 in a clockwise direction about a quarter of a turn, as shown in Fig. 3. When the light support is rotated, the lugs 27 thereon engage the cam or wedge surfaces 22 and the support 23 is gradually depressed until the light terminal 33 contacts with battery terminal 14 to close the 50 electric lighting circuit. To open the circuit, the light support 23 may be rotated in a reverse direction until the position shown in Fig. 2 is again assumed.

In some dry cell batteries, there is no metal top 65 to the battery but simply an entire covering of insulating composition. In this type of battery, as shown in Fig. 5, the fibrous jacket 11 may be cut to provide openings 34 and the depending rim or skirt portion 18 of the cap member 17 may be 70 provided with inwardly projecting lugs 35 to register with the openings 34 in the jacket whereby to engage the metal portion of the battery so that an electric circuit may be completed in the manner previously described.

75 To assemble the cap assembly, the light sup-

port 23 and the friction ring 30 are interfitted with the coil spring 32 in position therebetween. The assembly of light support and friction ring are then inserted in the opening in the cap member 17 which is then slipped over the terminal end of the battery and frictionally held thereon.

80 From the foregoing description, it will be apparent that the present invention provides a novel device which may be applied to the end of a dry cell battery whereby to furnish an extremely efficient and inexpensive flashlight which permits the ready removal and replacement of the batteries.

85 It is, of course, obvious that minor changes in details of construction and arrangement of parts may be made without departing from the scope of the present invention as set forth in the appended claims.

Having thus fully described my invention, 20 what I claim as new and desire to secure by Letters Patent, is:—

1. A flashlight comprising a battery, a cap member adapted to frictionally engage said battery, said cap member having an opening above the battery, cam surfaces around the edge of the opening in said cap member, a light bulb supporting member adapted to telescope within the opening in said cap member, means on said supporting member for engaging said cam surfaces to close an electric circuit upon rotation of said supporting member in one direction and said cam surfaces being adapted to limit the rotation of said supporting member in the opposite direction, and means for normally holding the light bulb terminal out of contact with the battery terminal.

2. A flashlight comprising a battery, a cap member adapted to frictionally engage said battery at the terminal end thereof, said cap member having an opening above the battery terminal, a light bulb supporting member adapted to reciprocate within and relative to the opening in said cap member, means for limiting the outward movement of said supporting member, a friction ring interconnected with said light bulb supporting member and resting upon the end of the battery and encircling the battery terminal, and a coil spring seated in said ring and bearing against said supporting member whereby to normally hold the light bulb terminal out of contact with the battery terminal.

3. A flashlight comprising a battery, a cap member adapted to frictionally engage said battery and having an opening therein, a light bulb supporting member adapted to telescope within and relative to the opening in said cap member, means for limiting the outward movement of said supporting member, a friction ring interconnected with said light bulb supporting member and resting upon the end of said battery and encircling the battery terminal, and a coil spring seated in said friction ring and adapted to normally urge said supporting member away from the battery.

4. In a flashlight, a lamp supporting and switch assembly comprising a cap member having an opening therein, a lamp supporting member adapted to telescope within the opening in said cap member, cam surfaces on said cap member, lugs on said supporting member adapted to engage said cam surfaces, a friction ring having a horizontal flange, additional lugs on said supporting member adapted to engage said horizontal flange, and a spring member adapted to

normally urge said supporting member and said friction ring apart.

5. A flashlight comprising a battery, a cap member adapted to frictionally engage said battery and having an opening therein above the end of the battery, a lamp supporting member adapted to telescope within the opening in said cap member, a friction ring resting upon the battery and encircling the battery terminal, a 10 coil spring seated in said friction ring and adapted to normally urge said supporting member away from the battery, and means operative upon the rotation of said supporting member for causing the lamp terminal to engage the 15 battery terminal whereby to close an electric circuit.

6. A flashlight comprising a battery, a cap member adapted to engage the terminal end of said battery, said cap member having an opening therein, a supporting member adapted to fit within the opening in said cap member, a light bulb carried by said supporting member, means for connecting said supporting member to said cap member to permit a limited reciprocal 25 movement of said supporting member within the opening in said cap member, a resilient member having one end thereof bearing against said supporting member whereby to urge the same outwardly, and means connected to said supporting 30 member for receiving the opposite end of said resilient member.

7. In combination with a battery, a hollow cap member adapted to be fitted over the terminal end of said battery in fixed relation thereto, said cap member having an inwardly bent and depending peripheral portion above said battery, a lamp supporting member, means associated with said supporting member and the depending portion of said cap member for limiting the outward movement of said lamp supporting member, said lamp supporting member being movable inwardly to close an electric circuit, and means for normally urging said lamp supporting member outwardly to open the electric circuit.

8. In combination with a dry cell battery, a hollow cap member engaging the terminal end of said battery in fixed relation thereto and having an inwardly curled depending peripheral portion disposed above said battery, a supporting member fitted within the depending portion of said cap member and movable relative thereto, a light bulb carried by said supporting member, means on said supporting member for engaging the depending portion of said cap mem-

ber for limiting the outward movement thereof, said lamp supporting member being adapted to be forced inwardly whereby to contact the central light bulb terminal with one of the battery terminals, means for electrically connecting the 5 other battery terminal with the other light bulb terminal, and resilient means for normally urging said supporting member outwardly whereby to open the electric circuit.

9. In combination with a dry cell battery having an opening in the side covering thereof, a hollow cap member engaging the terminal end of said battery in fixed relation thereto, said cap member having an inwardly projecting portion adapted to enter the opening in said battery covering whereby to contact one terminal of said battery, a lamp supporting member interconnected with said cap member and adapted to move relative thereto, said supporting member being adapted to be urged inwardly 10 whereby to close the electric circuit by bringing the central terminal of the lamp into contact with the central battery terminal, and a spring member for normally urging said supporting member outwardly whereby to open the electric circuit.

10. A flashlight comprising, in combination, a battery, a cap member fixedly engaging the terminal end of said battery and having a central opening above said battery, a lamp supporting 30 member mounted for relative reciprocation within the opening in said cap member with a portion thereof protruding above said cap member, stop means for limiting the outward movement of said supporting member, and spring means 35 for normally urging said supporting member outwardly to a position wherein said stop means is brought into operation and wherein the electric circuit remains open.

11. A flashlight comprising, in combination, a 40 battery, a cap member fixedly engaging the terminal end of said battery and having a central opening above said battery, a lamp supporting member mounted within the opening in said cap member for reciprocation relative thereto, 45 resilient means for normally holding said supporting member in circuit opening position, said supporting member being depressible to momentarily close the electric circuit, and cam means operative upon the turning of said supporting 50 member for causing the lamp terminal to contact a battery terminal whereby to hold the electric circuit close.
